PROCESS OF PRODUCING AZO DYESTUFFS
ON THE FIBER

Charles Schwabe Parker, Charles Leonard Wall,
and Franklin Farrington, Bolton, England, as-
signors, by mesne assignments, to General Ani-
line Works, Inc., New York, N. Y., a corpora-
tion of Delaware

No Drawing. Application September 15, 1932,
Serial No. 633,376. In Great Britain Septem-
ber 25, 1931

3 Claims. (Cl. 8—5)

The present invention relates to a process of producing azo-dyestuffs on the fiber, more particularly it relates to improvements in dyeing fibers, yarns and fabrics with azo-dyestuffs.

In the usual method of producing azo-dyestuffs on the fiber, the material is impregnated with a solution of the substantive coupling component or "passive component", such as an arylide of 2,3-hydroxynaphthoic acid, acetoacetic acid, 2-hydroxyanthracene-3-carboxylic acid, ortho-hydroxy-benzocarbazole carboxylic acid or any other suitable substantive component, and then developed with a solution of a diazo-compound. After the treatment in the diazo-bath, the material is exposed to the air, thereupon passed through a hot bath containing sodium carbonate and then washed and soaped.

It is known that in many cases the coupling, especially with compounds of high molecular weight, takes place rather slowly and incompletely under the usual conditions. When using in the usual method a diazo-compound which couples slowly it can be observed that, due to the incomplete coupling, in the after-treatment of the dyeings, particularly in the soap bath, part of the diazo-compound which has not coupled is dissolved from the material.

Most diazonium salts are somewhat unstable except at very low temperatures. Some of the passive components also, such as the alkali metal salts of 2,3-hydroxynaphthoic acid arylamides, commonly known under the name "naphtholates", are not wholly stable under the conditions of coupling. Therefore, if the time of coupling is unduly prolonged, decomposition may take place with the production of undesired by-products.

The disadvantage is particularly annoying in the production of resist articles: The unchanged diazo-compound which comes off in the soap bath, often reacts with the coupling component present on those parts of the material where the resists (white or colored resists) were applied, thus staining or coloring the reserved parts.

We have now found that the rate of coupling is greatly accelerated by increase in temperature and that notwithstanding the higher degree of instability exhibited by the reagents, such as the diazonium salt, at these higher temperatures, improved results, such as much more completely coupled and darker dyeings, may be obtained by performing the coupling at elevated temperatures. It is necessary, of course, that the diazonium salt and the passive components shall be in intimate contact in the correct proportions for reaction when the temperature is raised to accelerate the

coupling. The process according to the present invention, therefore, consists in impregnating the goods with a passive component and with a solution of a diazonium salt in the correct proportions for coupling and then raising the temperature rapidly to a value substantially above atmospheric 5 temperature. The acceleration of the coupling is progressive with rise of temperature but, generally speaking, temperatures above 50° C. and preferably round about 100° to 110° C. are 10 desirable. Preferably, the impregnation is performed at a sufficiently low temperature to retard decomposition of the reagents.

The goods are most suitably impregnated with the passive component, such as an arylide of 2,3-hydroxynaphthoic acid or other suitable substantive coupling component, passed through a diazonium solution and then subjected to a heating operation. Thus they may, immediately after the impregnation, be dried by passing them over 15 drying tins. Such method of drying involves 20 heating very rapidly to temperatures round about 100° C. and under these circumstances the coupling takes place in time of the order of a few seconds.

Or the material after impregnation with the coupling component and treatment with the diazo solution is immediately passed through a heated space, for instance, through a steamer or through the space between heated plates.

The dyeings obtained by operating in accordance with the present invention are usually darker, in some cases they are 30 to 40 per cent stronger, than those obtained by the known processes, probably owing to the smaller amount of 35 decomposition of the components. There is less risk of injury to the goods from soiling by decomposition products.

An important advantage of the present invention is that mixtures of different diazonium salts 40 and salts which are ordinarily too slow in coupling to be dyed continuously or are not sufficiently soluble, may be utilized satisfactorily, by operating according to the method of the present invention.

The process of the present invention also is 45 of advantage in the production of resist effects, since a considerable amount of organic acid may be employed in the diazonium solution without injuriously affecting the coupling processes.

For performing the coupling at elevated temperatures there may be used the usual drying tins or other suitably heated cylinders.

If instead drying over tins it is preferred to use a steaming apparatus, there may be used the 55

usual construction, for instance, an apparatus provided with perforated steam-pipes and with guide rollers for the material. Another modification of carrying out the coupling at elevated temperatures is the use of heated plates, for instance, of flat hollow plates of iron or other metal, electrically heated plates or other suitably shaped heating devices. The heating plates are arranged in pairs facing each other at a suitable distance apart, so that there is a heated space between them through which the material is conducted.

Such use of heating plates is of advantage, for instance, in the production of resist articles. It is easily possible to arrange the heating plates and the guide rollers for the material in such a manner that the material, on its way from the diazo bath to the washing machine, is in contact with rollers only on its reverse (unprinted) side. This avoids removal of the printed resists from the material, as is possible, for example, if the printed side of the material is in contact with the rollers.

The new process may advantageously be applied to the production of dyeings on the fiber in the case of all slowly coupling diazo-compounds. Slowly coupling diazo-compounds are, for instance, those of bases of the general formula:

wherein R_1 means a substituted or unsubstituted aromatic radical and R_2 a substituted or unsubstituted iso-cyclic radical.

An exhaustive description of all possible slowly coupling diazo-compounds is not necessary, since those skilled in the art will immediately realize that the new process is applicable to all diazo-compounds which have a tendency to couple slowly and yield meager dyeings on the fiber.

The new method is, of course, also applicable if normally coupling diazo-compounds are used, since in all cases improved results are obtained and less injury occurs.

As will be seen, the characteristic feature of our process resides in the fact that the material after having been treated in the diazo bath, is subjected to a heating operation. The invention is not limited to a particular heating device. Instead of drying tins, steaming apparatus or heated plates or any other suitable construction may be used.

The following examples serve to illustrate the invention, but they are not intended to limit it thereto:

(1) A fabric of cotton impregnated with 1% of 2',3'-hydroxy-naphthoyl-aniline in the usual manner is padded in a diazo-solution containing:

3% of diazonium chloride of 4-amino-4'-methoxy-diphenylamine,
5% of Epsom salt (magnesium sulfate),
1% of formic acid,
dried over tins and soaped.

(2) A fabric prepared in 2½% 2',3'-hydroxy-naphthoyl-2,5-dimethoxy-1-aminobenzene in the usual manner is passed through a suspension of

7% of zinc chloride double salt of the diazo compound of α -amino-anthraquinone,
½% of tragacanth,
1% of acetic acid,
dried over heated cylinders and soaped.

(3) Upon a fabric prepared in 2% 2',3'-hydroxynaphthoyl-4-chloroaniline in the usual manner, is printed a resist consisting of:

75. 20 parts by weight of sodium sulfoxylate,

80 parts by weight of British gum thickening. The fabric is then padded through a diazo-solution prepared in the usual manner, containing:

2% of 4,4'-diaminodiphenylamine,

1% of formic acid,

dried at elevated temperature and washed. A white resist is obtained upon a navy ground.

(4) A fabric prepared in 2½% of 2',3'-hydroxynaphthoyl-2,5-dimethoxy-1-aminobenzene is padded through the nip in a diazo-solution containing:

1% of 2,5-dichloroaniline,

0.75% of 4,4'-diaminodiphenylamine, and dried at elevated temperature. The goods are soaped in the presence of one-quarter per 15 cent of caustic soda at the boil, when a brown shade is obtained.

In the above examples the rapid increase of temperature is obtained during the drying operation which is performed in the customary manner by passing the fabric over drying tins which are steam heated. Preferably the temperature of the tins, or at least of those over which the fabric first passes, is just below that which would cause the liquid upon the fabric to dry. The number of 25 tins and their preferred temperature is dependent upon the nature and weight of the fabric and the weight of liquor therein. With a fabric weighing 30 lbs. for 120 yards and taking out 28 lbs. of liquor per piece, 24 tins each of 18 inches diameter are suitable. All are steam heated, the last 20 at about 2 or 3 lbs. excess pressure.

(5) (a) *Grounding liquor*

12 grams of 2',3'-hydroxynaphthoyl-aniline are 35 made into a paste with
15 cc. of Turkey red oil and
15 cc. of caustic soda solution of 38° Bé., the whole is dissolved with boiling water and made up with water to 40

1 liter

Temperature of the grounding bath: 35° C.

The material is grounded on a foulard and dried in the hotflue. 45

(b) *Developing bath*

27 grams of diazonium chloride of 4-amino-4'-methoxy-diphenylamine are 50 made up with
973 cc. of cold water to

1 liter

Temperature of the developing bath: 15° C. to 55 20° C. The grounded and dried material is developed on a two-roller-foulard and immediately—without exposure to air—passed through a steamer. The steaming temperature is about 110° C. to 115° C. and the time of steaming about 60 30 seconds. Thereupon, the material is passed through a bath at 40° C. containing 5 cc. of hydrochloric acid of 20° Bé. per liter, rinsed and soaped at boiling temperature.

(6) The material which has been grounded and dried as indicated in Example 5 is printed with the following white resist:

250 grams of aluminium sulfate 1:1

500 grams of starch tragacanth thickening, 70

100 grams of kaolin powder,

150 grams of water.

1000 grams

The printed material is dried. 71

Developing bath

27 grams of diazonium chloride of 4-amino-4'-methoxy-diphenylamine are made up with

5 973 cc. of cold water to

1 liter

The material is developed on a two-roller-fou-
lard and immediately passed through a steamer. The steaming temperature is about 110° C. to 115° C. and the time of steaming about 30 seconds. Instead of using a steamer, the material may be passed through the space between heated plates arranged in pairs facing each other at a suitable distance apart, for instance, flat hollow iron plates heated by means of steam. Thereupon, the goods are passed through a bath at 80° C., containing 30 cc. of hydrochloric acid of 20° Bé. per liter, rinsed in cold water, passed through a bisulfite bath of 80° C. containing 15 cc. of sodium bisulfite solution of 38° Bé. per liter, rinsed and soaped. A white resist is obtained upon a blue ground.

(7) Grounding liquor: as indicated in Example 5.

Yellow resist

80 grams of the sulfuric acid ester salt of the leuco compound of 3.4.8.9-diben-
30 zpyrene-5.10-quinone,

70 grams of a mixture of ethyleneglycol, di-
hydroxy-ethyleneglycol and mono-
methylether,

205 grams of water,

400 grams of starch tragacanth thickening,

65 grams of sodium bisulfite of 38° Bé.,

10 grams of ammonium thiocyanate,

120 grams of chrome yellow, 60% paste
(=neutral lead chromate),

40 50 grams of kaolin paste 1:1

1000 grams

Development and further treatment as indicated in Example 6. A yellow resist is obtained upon a blue ground.

(8) Grounding liquor: as indicated in Example 5.

Green resist

50 80 grams of the sulfuric acid ester salt of the leuco compound of dimethoxydi-
benzanthrone,

80 grams of a mixture of ethyleneglycol, di-
hydroxy - ethylene - glycol and
monomethylether,

175 grams of water,

400 grams of starch-tragacanth thickening, 5

80 grams of sodium bisulfite of 38° Bé.,

15 grams of ammonium thiocyanate,

120 grams of chrome yellow, 60% paste (neu-
tral lead chromate),

50 grams of kaolin paste 1:1, 10

1000 grams

Development and further treatment as indi-
cated in Example 6. A green resist is obtained 15
upon a blue ground.

We claim:

1. In the process of producing azo-dyestuffs on
the fiber by impregnating the material with a so-
lution of a substantive azo-component and subse-
quent developing in a solution of a slowly cou-
pling diazo-compound, the step which comprises 20
subjecting the material, immediately after the
treatment with the diazo bath, to a dry-heating
operation at a temperature of about 100° C. to 25
about 110° C.

2. In the process of producing azo-dyestuffs on
the fiber by impregnating the material with a so-
lution of a substantive azo-component and subse-
quent developing in a solution of a slowly cou-
pling diazo-compound, the step which comprises 30
subjecting the material, immediately after the
treatment with the diazo bath, to a steaming op-
eration.

3. In the process of producing azo-dyestuffs on 35
the fiber by impregnating the material with a so-
lution of a 2,3-hydroxy-naphthoic acid arylide
and subsequent padding in a solution of a diazo-
nium salt of a base of the general formula:

40

wherein R_1 means a substituted or unsubstituted
aromatic radical and R_2 a substituted or unsub-
stituted isocyclic radical, in the correct propor-
tions for coupling, the step which comprises sub-
jecting the material, immediately after the treat-
ment with the diazo bath, to a rapid heating op-
eration in the neighborhood of 100° C. to 110° C. 45
